UNITED STATES PATENT OFFICE

CHARLES A. KUHNS, OF NIAGARA FALLS, NEW YORK

REFLECTOR

Application filed March 4, 1932. Serial No. 596,818.

This invention relates to reflectors, and in accordance with the present invention a reflector is provided that is especially adapted but not necessarily restricted for use in connection with automobile headlights.

The reflector according to the present invention is adjustable toward and away from the electric lamp or bulb and to any angle of inclination as found desirable.

10 The invention together with its numerous objects and advantages will be best understood from a study of the following description, taken in connection with the accompanying drawing wherein:

15 Figure 1 is a front elevational view of a conventional automobile headlight, a portion of the lens being broken away to show the arrangement of the reflector in the headlight casing.

20 Figure 2 is a sectional view taken substantially on the line 2—2 of Figure 1.

Figure 3 is a sectional view through the reflector per se.

25 Figure 4 is a sectional elevational view through a longitudinally adjustable pivoted support member.

Referring more in detail to the drawing it will be seen that 5 designates generally the 30 casing of a conventional automobile headlight, and 6 the lens. Suitably mounted within the casing is the conventional electric lamp or bulb 7.

The improved reflector designated by the 35 reference character 8 is substantially cup-shaped so as to fit over the forward portion of the bulb 7, and the concave or inner side of the reflector is nickelized or otherwise treated to provide an efficient reflecting surface.

40 The reflector 8 is provided with an attaching bracket 9 which in the present instance is formed from a single length of wire bent and shaped to a substantial V with the sides of the V at the open end thereof welded or otherwise secured to the outer side of the reflector 8 at diametrically opposite sides of the reflector. At the apex of the V, the bracket 9 is bent inwardly into the shape of a U to provide a pair of opposed spring 45 jaws 10.

A base plate 11 is suitably secured to the bottom of the casing 5 inwardly thereof and adjacent the forward end of the casing. The plate 11 has ears 12 extending upwardly therefrom and the ears 12 support therebetween a hinge pin 13. A substantially fork shaped member comprises a sleeve like or tubular shank 14 that is internally threaded, and merges at one end into a pair of relatively spaced prongs or extensions 15 which adjacent their free ends are suitably apertured and through said apertures extends the pivot pin 13.

A shank 16 has a threaded end portion 65 screwed into the sleeve 14 and a flattened end portion 17 that is adapted to be inserted into the U provided at the apex of the bracket 9 and gripped on relatively opposite sides by the spring jaws 10 whereby the bracket is pivotally engaged with the shank 16 and by reason of the frictional engagement of the jaws 10 with the flattened end 17 of the shank 70 the reflector 8 may be disposed at any desired angle relative to the shank 16.

A coil spring 18 is disposed about an end 75 portion of the hinge pin 13, and one end 18a of the spring engages an adjacent ear 12, while the other end of the spring engages the extensions 15 and normally urges said extension and associated parts to rotate in a clockwise direction whereby the reflector 8 is 80 yieldably retained in engagement with the lamp bulb 7.

From the foregoing it is apparent that by 85 reason of threaded engagement of shank 16 and sleeve 14, these parts may be readily adjusted as may be required by the size of the headlight with which the reflector is used.

In actual practice, it will be found that 90 with a reflector of this character used in conjunction with a headlight, the light will be directed downwardly and over a material area of the road enabling the driver of the vehicle to have a clear vision, and such a reflector will be found especially useful when 95 driving in a fog. Further, by use of the reflector, glare is, if not actually obviated, reduced to a minimum thus obviating the necessity of dimming the lights when a car approaches from an opposite direction.

Even though I have herein shown and described the preferred embodiment of the invention, it is to be understood that the same is susceptible to further changes in the construction, combination and arrangement of parts and accordingly I claim all such forms of the invention to which I am entitled in view of the requirements of the prior art and scope of the appended claims.

10 Having thus described my invention, what I claim as new is:

1. In a headlight, in combination, a casing, a lamp mounted in said casing, an auxiliary reflector engaging said lamp and having its axis disposed at an angle to the axis of said lamp, and means for yieldably retaining said auxiliary reflector in engagement with said lamp; said means comprising a bracket fixedly secured within said casing, a fork having the legs thereof pivotally engaged with the bracket, spring means engaging said bracket and fork and normally urging the latter to rotate in one direction, said fork also having a shank provided with a threaded opening therethrough, a rod having an end screw threadedly engaged with the shank of said fork and having its other end flattened, and spring arms secured at one end to said auxiliary reflector and having remote 20 from said auxiliary reflector parallel portions frictionally engaging therebetween the flattened end of said shank.

2. An anti-glare device for vehicle headlights comprising a concavo-convex auxiliary reflector adapted to engage the lamp of the headlight with its axis arranged at an angle to the axis of said lamp, and supporting means for said auxiliary reflector yieldably urging said reflector into engagement 30 with said lamp, said supporting means including a bracket adapted to be attached to the usual headlight reflector, a longitudinally extensible supporting member pivotally connected at one end to said bracket, and having 40 at its other end a flattened portion, and a V-shaped bracket having sides secured to the auxiliary reflector at the open end of the V and at the apex of the V merging into clamping jaws frictionally engaging the flattened 50 end of said supporting member.

In testimony whereof I affix my signature.

CHARLES A. KUHNS.
